UNITED STATES PATENT OFFICE.

CHARLES A. KETTERER, OF EAST ST. LOUIS, ILLINOIS.

REFRIGERATOR.

1,222,635.

Specification of Letters Patent.

Patented Apr. 17, 1917.

Application filed March 29, 1915. Serial No. 17,749.

To all whom it may concern:

Be it known that I, CHARLES A. KETTERER, a citizen of the United States, and resident of East St. Louis, Illinois, have invented 5 certain new and useful Improvements in Refrigerators, of which the following is a specification containing a full, clear, and exact description, reference being had to the accompanying drawings, forming a part 10 hereof.

My invention relates to improvements in refrigerators, of the type shown and described in Patent No. 1,181,772 granted to me May 2, 1916, wherein a container for 15 cracked ice and salt is provided with vertically disposed flues exposed to the ice and salt and through which air is passed, cooled and directed into the refrigerator body.

The object of the improvements in this 20 application is to construct the air flues of sections of different diameters and varying lengths in order that the overflow points will be at different levels in the various flues whereby to provide for overflow from 25 the salt and ice through each flue regardless of the level of the refrigerator, as a whole.

With the above object in view, my improvements consist in certain novel features of the construction and arrangement of parts 30 which I will fully describe, specifically point out in my claims and illustrate in the accompanying drawings, in which:

Figure 1 is a longitudinal sectional elevation of a refrigerator embodying my improvements;

Fig. 2 is a sectional plan taken on the line 2—2 of Fig. 1;

Fig. 3 is an enlarged plan of the uppermost section of one of the flues showing the 40 screen for the upper, open end thereof; and

Fig. 4 is a fragmental, vertical sectional elevation of the flue showing the screen.

Referring by numerals to the accompanying drawings:

5 designates the refrigerator body, the side walls 6 of which may be of any approved, insulated construction, and which has at its rear the hinged doors 7 and at its top the hinged door 8, the former providing access to the refrigerator body for purposes of cleaning and repair, and the latter providing access to the ice container.

Extending from the refrigerator are one or more display cases 9 whose interiors are 55 in direct communication with the refriger-

ator and whose walls are of any approved insulated construction and preferably glazed, so that wares may be displayed therein.

The ice and salt container which is placed 80 in the refrigerator comprises a lower section 10 which, as shown, is rectangular in plan, and of hopper shape. At each corner there is a support in the form of an angle iron 11^a, and to which the section 10 is 85 secured.

The inclined lower walls of this section 10 are each perforated at intervals and in each perforation there is inserted a tube 11, which are each flanged at their lower ends 70 for securing about said perforations. These tubes 11 are of varying heights, are preferably made of corrugated sheet metal, and each tube has adjacent its upper end a transverse rod 12. Slipped into each tube 11 and 75 supported on the rod 12 is a tube 13, of plain sheet metal, and like the tubes 11 the tubes 13 are of varying heights, and have at their upper ends the transverse rods 14.

Slipped into the upper ends of the tubes 80 13 are the tubes 15 which rest upon the rods 14 and are of varying heights with their upper ends in substantially the same plane. These tubes 15 are made of corrugated sheet material and each has at its upper end a 85 crimp 16 which constitutes a support for a screen 17, designed primarily to prevent ice from falling through the tubes when being supplied to the container, and which screen I prefer to make of a single strip of sheet 90 metal in the form of a spiral.

The upper section 18 of the ice container is of rectangular form in plan and is secured to the supports 11^a, with its lower end overlapping the upper end of the lower section and spaced therefrom by said supports.

This upper section extends to substantially the level of the upper ends of the uppermost tubes, and which is by preference the full height of the refrigerator body, 100 except such spacing as is required to furnish air to the tubes from the top of the refrigerator. Over the top of the container there is a cover 19, having openings 20 registering with the tubes. This cover is 105 designed to form with the body of the container a complete closure for the ice and salt in order to minimize moisture in the refrigerator as well as to conserve ice.

At the bottom of the container I provide 110

a drain cock, which is by preference kept open when the refrigerator is iced and in use.

In arranging the walls of the container of 5 overlapping and laterally spaced wall sections it is apparent that brine from the salt and ice will flow between the spaced walls, down the exterior wall of the lower section and remove any accumulated frost and prevent further accumulation of frost so long 10 as the level of ice and salt is above said spaced wall portions.

All the tubes are made of the laterally spaced sections for the same reason as given 15 for the container walls and I find that air in passing downwardly through "clean" tubes uninsulated with heavy coats of frost will more nearly become the temperature of the ice and salt, than when passed over or 20 between surfaces which are laden with accumulated frost.

The construction of the tubes shown, *i. e.*, of alternate plain and corrugated cylinders I consider one inexpensive and practicable 25 way of providing openings at intervals into the ice and salt container, but do not wish to be considered as limiting myself to this one form, as many modifications suggest one form, as many modifications suggest themselves to me, and will be obvious to 30 others skilled in the art.

Copies of this patent may be obtained for five cents each, by addressing the "Commissioner of Patents, Washington, D. C."

What I claim as new and desire to secure by Letters Patent of the United States is:

1. In combination with a salt and ice container, a plurality of open ended tubes 35 extending through said container, each of said tubes being constructed of telescoping sections and certain of said sections being constructed of plain material and the remaining sections constructed of corrugated material, whereby to provide for the flow 40 of brine from the salt and ice container over the interior faces of said tubes.

2. In combination with a salt and ice container, a plurality of open ended tubes extended through the said container, each tube 45 being constructed of alternate plain and corrugated telescoping sections, the said sections varying in lengths in the several tubes to provide for the flow of brine from the container at different elevations into, and 50 over the interior surfaces of said tubes.

In testimony whereof, I have signed my name to this specification, in the presence of two subscribing witnesses.

CHARLES A. KETTERER.
